NON-RECIPROCAL ELECTRIC COUPLING DEVICE

Gerrit de Vries, Eindhoven, Netherlands, assignor to North American Philips Company, Inc., New York, N.Y., a corporation of Delaware

Filed Oct. 15, 1957, Ser. No. 690,384

Claims priority, application Netherlands Nov. 9, 1956

1 Claim. (Cl. 333—24)

This invention relates to non-reciprocal electric coupling devices, in which the transmission of energy in one direction is nil.

Such devices are used, for example, as a microwave insulator, for example in a connection between a generator and a load in order to suppress the reaction of the load upon the generator. A plurality of devices of this kind are already known in which a piece of pre-polarized high-frequency magnetic material, for example of ferrite, is arranged at a given area in a wave guide so that waves in the wave guide are passed substantially unhindered in one direction and materially damped in the other direction. However, such devices are not usable for comparatively low frequencies, for example of the order of 500 mc./s., since the dimensions of the wave guide would become too large for practical use.

Furthermore, a non-reciprocal electric coupling device is already known which comprises two crossing coils having their winding surfaces arranged at right angles to each other and surrounding a common core of high-frequency magnetic material which is pre-polarized in a direction parallel to the intersecting line of the winding surfaces. Such a coupling device is indicated in certain cases by the name of "gyrator." In such a gyrator, transmission of energy from one coil to the other may be eliminated by means of an external resistance coupling between the two coils. In the reverse direction, however, transmission of energy can take place. This device is not particularly suitable for waves having a wavelength of the order of 50 cms.

The non-reciprocal electric coupling device according to the invention likewise comprises two crossing windings surrounding a common core of high-frequency magnetic material which is pre-polarized in a direction parallel to the intersecting line of the winding surfaces. However, in the device according to the invention, the winding surfaces are at an angle between 0° and 90° and the pre-polarization has a value such that for a given frequency the transmission coefficient between the windings is nil. This device thus has no external coupling between the windings. If desired, the windings may each comprise a single turn.

In order that the invention may be more readily carried into effect, it will now be described more fully, by way of example, with reference to the accompanying drawing.

FIG. 1 shows two crossing Lecher lines 1 and 2, which are each short-circuited at one end to form a single turn and which surround a core 3 of high-frequency magnetic material. The planes in which the conductors of the Lecher lines 1 and 2 are situated are at an angle of φ to each other. The core is pre-polarized in a direction parallel to the intersecting line of said planes, as indicated by arrow H, by means (not shown), for example an electromagnet. Experiments have revealed that an angle φ between 0° and 90° corresponds to a field strength H, with which at a given frequency there is no transmission of energy from coil 1 to coil 2, but such transmission is possible in the reverse direction.

FIG. 2 shows the relationship between the coupling factor S between the coils 1 and 2 and the frequency f for different values H_1, H_2, H_3 and H_4 of the pre-polarizing field. From the figure it may be seen that the coupling

2

factor S corresponding to the field strength H_2 becomes nil for a frequency of 250 mc./s.

The foregoing may also be recognized theoretically as follows. The relationship between the components B_x and B_y of the magnetic inductance in directions at right angles to the magnetic pre-polarization and the corresponding components H_x and H_y of the magnetic field strength may in general be expressed by the relations:

$$B_x = \mu_1 H_x + \mu_2 H_y$$

$$B_y = \mu_2 H_x + \mu_1 H_y$$

wherein μ_1 and μ_2 indicate complex permeabilities. From the condition that the Lecher line 2 does not surround a magnetic field produced by current in the Lecher line 1, it follows that $\tan \varphi$ must be equal to $\mu_1 : \mu_2$. From the fact that μ_1 and μ_2 are complex values, it follows that two conditions must be fulfilled. The permeabilities μ_1 and μ_2 may approximately be expressed by the relations:

$$\mu_1 = 1 + \frac{\omega_{\text{res}} + j\frac{\beta}{2}}{\omega_{\text{res}} - \frac{\omega}{\omega_{\text{res}}} + j\frac{\beta}{2}} \left(\frac{\omega_{\text{ar}}^2}{\omega_{\text{res}}^2} - 1 \right)$$

$$\mu_2 = \frac{j}{\omega_{\text{res}} - \frac{\omega}{\omega_{\text{res}}} + j\beta} \left(\frac{\omega_{\text{ar}}^2}{\omega_{\text{res}}^2} - 1 \right)$$

wherein ω indicates the angular frequency, ω_{res} the angular frequency at which for the given value of the pre-polarizing field H magnetic resonance of the high-frequency material occurs, and ω_{ar} the angular frequency at which the magnetic material is in anti-resonance, that is to say at which the real part of the permeability μ_1 , which indicates the relationship between a component of the magnetic inductance in a direction at right angles to the pre-polarization and the component of the magnetic field in the same direction, is nil. In the above-mentioned formulae, β indicates a magnitude which is proportional to the magnetic losses of the material, and j is equal to the root of -1 . Upon substitution of the above-mentioned relations of μ_1 and μ_2 in the condition

$$\tan \varphi = \frac{\mu_1}{\mu_2}$$

45 we have $\omega = \omega_{\text{ar}}$ and

$$\tan \varphi = \frac{\beta}{2} \frac{\omega_{\text{ar}}^2 + \omega_{\text{res}}^2}{\omega_{\text{ar}}^2 - \omega_{\text{res}}^2}$$

From this it follows that, in order to suppress transmission of energy from the Lecher line 1 to the Lecher line 2, the pre-polarizing field for a given frequency ω must be adjusted to a value such that the magnetic material of the core 3 is in magnetic anti-resonance for this frequency.

55 What is claimed is:

A non-reciprocal electrical coupling device comprising a core of high-frequency magnetic material, a first winding positioned to surround said core and lying substantially in a first plane, a second winding positioned to surround said core and lying substantially in a second plane, said windings being oriented with respect to each other so that said first and second planes intersect each other at an angle lying between the values of zero and ninety degrees, and means for pre-polarizing said core in a direction parallel to the line of intersection of said first and second planes, said pre-polarization having a value to cause said core material to be substantially in magnetic anti-resonance at a predetermined frequency whereby the signal transmission coefficient between said windings is substantially zero in one direction at said frequency determined by the value of said pre-polarization.
